SWIVEL HARP FIXTURE FOR ELECTRIC LAMPS

Kornel Berger, New York, N. Y.

Application March 18, 1935, Serial No. 11,583

2 Claims. (Cl. 240—148)

This invention relates to new and useful improvements in a swivel harp fixture for electric lamps.

The invention relates particularly to means for frictionally controlling the swivelling of a stud on the frame of an article as mentioned.

In a prior application and Patent No. 1,974,947, I have disclosed means for frictionally controlling the swivelling of the stud on the frame characterized by the contacting of a washer with the frame. This invention contemplates the formation of the washer in such a manner as to better take advantage of the resiliency of the body of the washer to supplement the frictional contact between the washer and the frame.

More particularly, the invention proposes the use of a washer having diametrically opposite areas thereof bent downwards against the frame in such a manner that the edges of the washer engage the frame with resilient effect for providing the frictional means desired.

A still further object of the invention is the provision of grooves upon the down-turned areas arranged so as to increase the contacting areas of the washer with the frame to increase the frictional resistance between the parts.

Another object of the invention is the construction of an article as mentioned which is simple and durable and which can be manufactured and sold at a reasonable cost.

For further comprehension of the invention, and of the objects and advantages thereof, reference will be had to the following description and accompanying drawing, and to the appended claims in which the various novel features are more particularly set forth.

In the accompanying drawing forming a material part of this disclosure:

Fig. 1 is a side elevational view of a lamp with a lamp shade frame mounted upon a swivel harp fixture constructed according to this invention.

Fig. 2 is an enlarged perspective detailed view of the swivel harp fixture illustrated per se.

Fig. 3 is a side elevational view of the upper portion of Fig. 2 to better illustrate that portion of the device embodying the invention.

Fig. 4 is a side elevational view of Fig. 3 looking in the direction of the line 4—4 of Fig. 3.

Fig. 5 is a view similar to Fig. 4, but illustrating another embodiment of the invention.

Fig. 6 is a side elevational view of Fig. 5 looking in the direction of the arrow 6—6 of Fig. 5.

In Fig. 1 a lamp base 10 is illustrated provided with a lamp socket 11 supporting a lamp 12. A harp fixture 13 is mounted upon the lamp

and supports a shade frame 14. This shade frame is held in position by a spherical shaped nut 15. The invention particularly relates to a friction means associated with a stud mounted upon the top of the frame 13 for coaction with the nut 15 to hold the lamp shade in position so that the shade may be tilted in one direction or the other direction to various degrees. This frictional means comprises a washer 17 mounted upon the stud and engaging against a portion of the frame 14. It is the formation of this washer that forms the basis of this invention.

The washer 17 has diametrically opposite areas 17^a bent downwards to engage against the frame. The stud 16 is formed with a flange portion 16^a against which the washer 17 rests. The washer 17 is formed with a central opening through which the lower portion 16^b of the stud engages. A section of the frame 14 passes through an opening in the lower portion 16^b of the stud. The bent area 17^a of the washer resiliently engages against the frame in such a manner that the inherent resilient action of the washer is utilized to produce the frictional resistance for holding the stud in various swivelled positions on the frame.

In the form of the invention illustrated in Figs. 5 and 6 the bent areas 17^a are formed with grooves 17^b adapted to engage against the frame 14 so as to increase the contacting areas between the washer and the frame. These grooves 17^b are formed by bending the material of the washer. More particularly, the base walls of the grooves are pressed against the top of the frame. With this construction there will be a pressure between the washer and the frame due to the resiliency of the washer in its bent form, and this pressure will be distributed throughout the contacting areas of the washer and the frame.

While I have illustrated and described the preferred embodiment of my invention it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. In a swivel harp fixture for mounting a shade on an electric lamp, consisting of a wire harp frame, and a stud swivelly mounted on a portion of said frame for supporting said shade, and means for detachably securing said shade to said stud, means for frictionally controlling the swivelling of said stud, comprising a washer of

resilient material rotatably mounted on said frame, said washer being of substantially uniform thickness and having diametrically opposed edges bent for frictionally engaging said frame 5
6 whereby said washer resiliently holds said stud relatively rigid with said frame.

2. In a swivel harp fixture for mounting a shade on an electric lamp, consisting of a wire harp frame, and a stud swivelly mounted on a 10 portion of said frame for supporting said shade, and means for detachably securing said shade to said stud, means for frictionally controlling the

swivelling of said stud, comprising a washer of resilient material rotatably mounted on said frame, said washer being of substantially uniform thickness and having diametrically opposed edge portions bent for frictionally engaging said frame, said edge portions being bent to form grooves in their sides adjacent said frame for increasing the areas of contact between said washer and said frame, whereby said washer resiliently holds said stud relatively rigid with said frame. 10 5

KORNEL BERGER.
